DRILL STEEL RETAINER

John C. Curtis, Garfield Heights, Ohio, assignor
to The Cleveland Rock Drill Company, Cleve-
land, Ohio, a corporation of Ohio

Application March 13, 1936, Serial No. 68,744

11 Claims. (Cl. 121—32)

This invention relates broadly to rock drills of the percussive type, but more particularly to improvements in drill steel retainer therefor.

One object of this invention is to produce a 5 releasable drill steel retainer of simple construction which is strong, durable and efficient.

Another object of this invention is to produce a 10 tool retainer with resilient means acting on the retainer for locking it in operative or inoperative position, and simultaneously absorbing the 15 shocks or blows of the drill steel against the retainer.

Other objects of this invention will be apparent 20 from the following detailed description wherein 15 similar characters of reference designate corresponding parts and wherein:

Fig. 1 is a side elevational view of the front 25 portion of a rock drill illustrating the improved retainer in operative position.

Fig. 2 is a view similar to Fig. 1 illustrating the 30 retainer in inoperative position.

Fig. 3 is a longitudinal sectional view taken in 35 a plane indicated by line 3—3 in Fig. 1 and looking in the direction of the arrows shown therein.

Figs. 4 and 5 are views similar to Figs. 1 and 2 40 respectively, illustrating a modification of the invention.

Fig. 6 is a view similar to Fig. 3, but taken in a 45 plane indicated by line 6—6 in Fig. 4.

Referring to the drawings, 10 represents the 50 front end housing of a rock drill having the shank 11 of a drill steel 12 slidable therein. This drill steel has a collar 13 formed integral thereon, and 55 engageable with the front end of the housing 10 to limit the penetration of the shank 11 within the former. The front end of the housing 11 is substantially cylindrical except for a boss or enlargement 14 formed on one side thereof. This 60 boss has an opening 15 of oblong shape formed therethrough and adapted to accommodate within the bottom part thereof a substantially cylindrical rubber buffer 16, which is centrally apertured as at 16' to permit its compression.

In order to prevent the accidental removal of 65 the drill steel 12 from the front housing, there is a yoke 17 partly encircling the drill steel ahead of its collar 13, and capable of engagement with the latter. This yoke has two parallel arms 18 70 extending upwardly therefrom to the boss 14 of the housing 10. The free end of the arms 18 are enlarged on one side as at 19, and transversally apertured to receive a shaft or bolt 20 which extends through the apertured boss 14. The end 75 portions of this shaft engages the side arms of the yoke 17 to serve as a pivot for the latter. One

end of the shaft or bolt 20 is formed with a head 21 shaped for interlocking engagement with a shoulder 22 provided on the adjacent arm of the yoke, thus preventing the rotation of the bolt 20 relative to the yoke 17. The other end of the bolt 20 is formed with a reduced screw threaded portion 80 adapted to receive a nut 23 engageable with the adjacent arm 18 of the yoke 17, which arm may thereby be clamped between the nut 23 and an annular shoulder 24 formed on the shaft 20 at the end of its reduced portion.

Interposed between the shaft 20 and the rubber buffer 16, there is slidable in the oblong opening 15, but locked therein against rotation, a substantially rectangular member or block 25. This 15 block has its end portions protruding from the side walls of the boss 14 to form movable lugs 26 having the upper wall 27 thereof machined perfectly flat, and forming at the inner end of each lug a shoulder 28 engageable with the side arms 20 18 to prevent the accidental removal in a lengthwise direction of the block 25 from the aperture 15. The under side of the block 25 is recessed to form an arcuated seat 29 for the rubber buffer 16, and two side walls or shoulders 34 engaging 25 the end walls of the buffer 16 for preventing the lengthwise movement of the buffer.

The free end of the arms 18 are provided with two diverging inclined surfaces 30 and 31 engageable with the upper wall 27 of the lugs 26, and 30 causing thereby the compression of the rubber buffer 16.

In the modification shown in Figs. 4 to 6 inclusive, the shaft 20 has been made an integral part 35 32 of the arms 18. To permit the assembly of this modified construction, the side wall of the front housing boss 14 has been cut open as at 33, thus allowing the integral shaft portion 32 of the retainer, to be introduced in the oblong aperture 15, after the insertion of the rubber buffer 16 and 40 block 25.

After the device has been assembled, it will be noted that the block 25 engaging the rubber buffer 16 will cause a relatively slight compression 45 of the latter due to the engagement of the inclined surfaces 30 or 31 with the upper wall 27 of the lugs 26. It will also be observed that when the retainer is positioned as shown in Figs. 1 and 4, that is in operative position, the blows transmitted by the collar 17 of the drill steel 12 to the yoke 17, will be 50 absorbed or at least greatly cushioned by the rubber buffer 16.

In addition to the cushioning action of the rubber buffer 16, the latter causes the forcible 55 engagement of the upper wall 27 of the lugs 26

with either diverging surfaces 30 and 31 of the arms 18, thus maintaining the yoke 17 in either operative or inoperative position.

When it is desired to remove the drill steel from the housing 10, the yoke 17 may be rocked from the position shown in Fig. 1 to the position shown in Fig. 2. In this instance, the point of convergence of the surfaces 30 and 31 passing over the lugs 26, will cause a greater compression of the rubber buffer 16. When finally the surfaces 31 engage the lugs 26 as shown in Figs. 2 and 5, the retainer will again be locked against accidental movement.

By means of this construction, the blows imparted to the yoke 17 by the collar of the drill steel 17, will tend to drive the retainer away from the housing 10, and thereby increasing the frictional engagement of the surfaces 30 with the lugs 27 to positively prevent the rocking movement of the retainer into inoperative position.

Although the foregoing description is necessarily of a detailed character, in order to completely set forth the invention, it is to be understood that the specific terminology is not intended to be restrictive or confining and it is to be further understood that various rearrangements of parts and modification of structural detail may be resorted to without departing from the scope or spirit of the invention as herein claimed.

I claim:

1. A retainer for a rock drill comprising in combination with a housing and a drill steel, a boss on one side of said housing having an aperture extending therethrough, a yoke for retaining the drill steel in said housing movable into operative or inoperative position relative to said drill steel, side arms extending upwardly from said yoke, an element extending through said aperture carried by said side arms to serve as a pivot for said yoke, and a resiliently supported member within said aperture having end portions engaging said side arms to carry the yoke in operative or inoperative position relative to the drill steel.

45 2. A retainer for a rock drill comprising in combination with a housing and a drill steel, a boss on one side of said housing having an aperture extending therethrough, a yoke for retaining the drill steel in said housing movable into operative or inoperative position relative to said drill steel, side arms extending upwardly from said yoke, a shaft like element extending through said aperture and engaging said side arms to serve as a pivot for said yoke, and resiliently supported means within said aperture having end portions protruding therefrom and engaging said side arms for carrying the yoke independently of said shaft like element.

60 3. A retainer for a rock drill comprising in combination with a housing and a drill steel, a boss on one side of said housing having an aperture extending therethrough, a yoke for retaining the drill steel in said housing movable into operative or inoperative position relative to said drill steel, side arms extending upwardly from said yoke, an element through said aperture engaging said side arms to serve as a pivot for said yoke, a member resiliently supported within said aperture and having end portions protruding therefrom in carrying engagement with said side arms, and means on said end portions and side arms capable of interengagement for locking said yoke in operative position.

75 4. A retainer for a rock drill comprising in combination with a housing and a drill steel,

a boss on one side of said housing having an aperture extending therethrough, a yoke for retaining the drill steel in said housing movable into operative or inoperative position relative to said drill steel, side arms extending upwardly from said yoke, an element extending through said aperture and engaging said side arms to serve as a pivot for said yoke, a member extending through said aperture and engaging said side arms to carry said yoke and lock the same in position, and a rubber buffer in said aperture acting on said member to cushion the yoke and to press said member into interlocking engagement with said side arms.

5 5. A retainer for a rock drill comprising in combination with a housing and a drill steel, a boss on one side of said housing having an aperture extending therethrough, a yoke for retaining the drill steel in said housing movable into operative or inoperative position relative to said drill steel, side arms extending upwardly from said yoke, means within said aperture engaging said side arms to serve as a pivot for the yoke, movable lugs carried by said housing engaging said side arms for suspending said yoke thereon and for locking the same in position, and resilient means within said aperture acting on said lugs to cushion said yoke and press said lugs into interlocking engagement with said side arms.

10 6. A retainer for a rock drill comprising in combination with a housing and a drill steel, an enlargement on one side of said housing having an aperture extending therethrough, an element extending through said aperture and having lugs formed thereon, a rubber buffer within said aperture supporting said element, a yoke for retaining the drill steel in said housing, side arms extending upwardly from said yoke and having flat surfaces resting on the lugs of said element, and means within said aperture engaging said side arms above said element for preventing the upward movement of said side arms and thereby causing the forcible interlocking engagement of the lugs of said element with the flat surfaces of said side arms by compressing said rubber buffer.

15 7. A retainer for a rock drill comprising in combination with a housing and a drill steel, an enlargement on one side of said housing having an aperture extending therethrough, an element extending through said aperture and having lugs formed thereon, a rubber buffer within said aperture supporting said element, a yoke for retaining the drill steel in said housing, side arms extending upwardly from said yoke and having flat surfaces resting on the lugs of said element, and means carried by said side arms engaging said housing above said element to limit the upward movement of said side arms and to compress said rubber buffer for effecting the forcible interengagement of the flat surfaces of said side arms with the lugs of said element.

20 8. A retainer for a rock drill comprising in combination with a housing and a drill steel, an enlargement on one side of said housing having an aperture extending therethrough, a yoke for retaining the drill steel in said housing, side arms extending upwardly from said yoke, a shaft like element extending through said aperture and engaging said side arms to serve as a pivot for said yoke, a substantially rectangular block extending through said aperture having its ends protruding therefrom, diverging flat surfaces on said side arms capable of interlocking engagement with the protruding end of said block for holding said yoke in position, and resilient means within

said aperture supporting said block and acting thereon for forcibly effecting the interlocking engagement aforesaid.

9. A retainer for a rock drill comprising in combination with a housing and a drill steel, an enlargement on one side of said housing having an aperture extending therethrough, a substantially rectangular block within said aperture having its ends protruding therefrom, a yoke for retaining the drill steel in said housing, side arms extending upwardly from said yoke, a pivotal connection between said side arms and housing, said side arms resting on the protruding ends of said block for supporting said yoke, diverging flat surfaces on said arms capable of interlocking engagement with the protruding ends of said block for holding said yoke in position, and a rubber buffer within said aperture supporting said block and acting thereon for forcibly effecting the interlocking engagement aforesaid.

10. A retainer for a rock drill comprising in combination with a housing and a drill steel, a boss on one side of said housing having an aperture extending therethrough, a yoke for retaining the drill steel in said housing, side arms extending upwardly from said yoke, a pivotal con-

nection between said side arms and housing, a rubber buffer within said aperture, an element extending through said aperture supported by said rubber buffer, said element having end portions in carrying engagement with the side arms of said yoke, means for locking said element against lengthwise movement, and means depending from the end portions of said element engageable with the end walls of said rubber buffer for preventing the lengthwise movement of said buffer.

11. A retainer for a rock drill comprising in combination with a housing and a drill steel, a transversely disposed aperture on one side of said housing, a yoke for retaining the drill steel in said housing, side arms extending upwardly from said yoke, means carried by said housing engaging said side arms to serve as a pivot for said yoke, an element extending through said aperture in carrying engagement with said side arms, a resilient buffer within said aperture supporting said element, and means on said element engaging said side arms and said buffer for preventing the lengthwise movement of said element and buffer relative to said housing.

JOHN C. CURTIS.
